UNITED STATES PATENT OFFICE.

ERNEST W. BRACKETT, OF ELYRIA, OHIO, ASSIGNOR TO THE DEAN ELECTRIC COMPANY, OF ELYRIA, OHIO, A CORPORATION OF OHIO.

ELECTRICAL SWITCH.

No. 845,848.

Specification of Letters Patent.

Patented March 5, 1907.

Application filed March 31, 1904. Serial No. 200,900.

To all whom it may concern:

Be it known that I, ERNEST W. BRACKETT, a citizen of the United States, residing at Elyria, in the county of Lorain and State of Ohio, have invented a certain new and useful Improvement in Electrical Switches, of which the following is a specification, reference being had therein to the accompanying drawing.

10 My invention relates to electrical switches, and has for its object the improvement of such devices.

It relates particularly to such switches as are used in connection with telephone instruments, although it has some features which would render it useful in any part of the electrical field.

15 The type of switch-hook now most commonly employed upon subscriber's telephone wall sets is known as the "long-lever" hook. In the early days of the art, before refinements of design had been introduced into all the details of telephone apparatus, there was no settled common form of hook, much of the 20 uncertainty and a large proportion of the troubles at the subscriber's instrument being due to bad springs and poor contacts. Many of the early hooks and some still in use were designed with short levers and springs which 25 from their shape, position, or size were almost certain to acquire a "set." At the same time rubbing contacts were used, formed usually by a German silver spring coöperating with some moving part of the 30 brass hook-lever. Contrary to the purpose of their design such rubbing contacts have been found to accumulate dirt and to corrode, and they are now being gradually superseded by platinum contacts mounted on 35 suitable surfaces or springs.

40 In spite of the many improvements that have recently been made most switch-hooks still remain subject to many criticisms, because of inherent weaknesses of design not yet entirely eliminated. Thus with most hooks of which I have knowledge it is necessary to put the hook in position from the inside of its housing, and thereafter to apply the escutcheon, which must necessarily be divided. In 45 some cases the base of the hook is secured on the inside of the box and the lever then inserted from the outside and the hook assembled. This is very poor practice, however, as all separate parts of the mechanism should

be assembled complete before they are 55 brought together, as well for the sake of uniformity in product as for shop economies. In some cases, and especially in central-energy wall sets, the side brackets of the desk have been divided and the hook-lever mounted to project through the notched face of one portion, being inclosed when the parts are in 60 position. This also involves the use of a divided escutcheon. In most of the long-lever hooks now on the market the lever is pivoted 65 on a shoulder-screw, and if this screw happens to work loose the action of the lever on the contacts becomes uncertain, with a possibility of its working off entirely. If in order to avoid this the screw be riveted after it is 70 in, it then becomes impossible to remove the lever for purposes of inspection, repairs, &c. In almost all hooks now on the market the supporting-base for the hook is secured either to the bottom of the magneto-box or to the 75 transverse shelf or partition under the desk. In either case the hook is not permanently connected with the side wall through which it passes. It cannot be compacted and compactly mounted, and in every case it requires 80 an escutcheon of one or several separate parts.

By my present invention I eliminate all the above and many other undesirable features hitherto existing in long-lever switch-hooks. Moreover, I secure a certainty of 85 operation and a uniformity of product not hitherto attainable.

My hook consists, essentially, of only four parts—viz., first, the frame; second, the 90 group of contact-springs; third, the actuating-spring, and, fourth, the lever.

First. The frame is made in one piece and carries the escutcheon on it.

Second. The contact-springs are mounted 95 as a unit and handled as such.

Third. The spring is of the simplest form and one which has been found by many years experience in the manufacture of small-arms to maintain its strength and temper longer 100 than any other. It serves the double purpose of lifting the lever and of maintaining it upon its pivot.

Fourth. The lever is inserted through a slot of normal size in the escutcheon and frame, no special opening being required, and is slotted to take over the shouldered pivot-pin on the frame, the pin being riveted solidly 105

to the frame and the lever being held up and on it by the mainspring.

The proportions of all my parts are such that the entire hook when assembled may be inserted from the outside through the side opening in box or bracket, the escutcheon covering this opening and giving a handsome finish.

My invention is illustrated in the accompanying drawings, wherein—

Figure 1 is a side view of the hook assembled. Fig. 2 is a similar view with the contact-springs removed. Fig. 3 is a separate view of the frame in perspective, and Fig. 4 of the escutcheon-plate detached.

In Figs. 1 and 2 the appearance of the members as they are assembled is clearly shown. The frame A carries the escutcheon A' at one extremity, and at the other extremity a' carries the pivot-pin a⁵. This frame and the escutcheon are best shown in Figs. 3 and 4. Both frame and escutcheon are formed up out of blanks punched from sheet metal. The frame consists of a longitudinal member a and a transverse member a'. The former has a projecting portion on its upper edge bent over to form a shelf or flange a⁴, which is perforated at a⁸ and a⁹ for the purpose of securing the actuating and the contact springs, respectively. A rounded extension a⁷ carries the abutment or pivot a⁵ for the hook-lever H. This consists of a cylindrical piece of metal, preferably cut from rod stock and with an annular depression cut in it at a⁶, so as to form a headed and shouldered pin.

The transverse portion a' of the frame has the vertical slot a³ cut parallel with the plane of the body a, the projecting ears a², and the four screw-holes a¹⁰. The purpose of having the ears a² projecting is to throw the body a inward from the edge of the escutcheon, so that the latter will cover the opening through which the hook is inserted.

While the transverse portion a' of the frame really forms an escutcheon in itself, it is not finished in its appearance by reason of its shape. Hence I provide a cover-plate A', which may obviously be of much thinner stock than that in the frame, as its purpose is largely ornamental. It is formed with a flange a¹¹ to fit about the periphery of the member a', as indicated by dotted lines in Figs. 1 and 2, and it also has a vertical slot a¹² and screw-holes a¹³, which when the parts are assembled register with the corresponding slot and screw-holes in the part a'.

Upon the frame is supported the lever H, having the usual forked extremity h. This lever extends through the slots a³ and a¹² in the escutcheon-plate and frame and back along the face of the member a, being slotted at h' and held up in the recess a⁶ of the pin a⁵ by the mainspring S'. This spring is formed with a portion substantially lying in a circle and a straight line extension constituting a

tangent thereto. This extension is secured upon the flange a⁴ of the frame by the screws s⁵, secured in the openings a⁸. Its curved end passes around the extension h³ of the hook-lever and coming up beneath it takes into a notch h², lying a little to the left of a vertical line through the center of the pivot a⁵. With this construction the spring holds up the lever and at the same time maintains it in position upon the pivot.

The contact-springs s are assembled in parallel relation with interposed slips of insulating material s' and secured by the screws s² to the metal block S. This block in turn is secured to the flange a⁴ by the screws s³, passing through the openings a⁹. The advantages of thus assembling the contact-springs upon a separate base are obvious. Sets for different purposes may be kept in stock and finished hooks assembled therefrom, as required. Thus for a single-party common-battery instrument a different arrangement of springs would be required from that intended for a magneto party-line telephone. Both can be kept in stock by my invention without any great expense, and all the hooks as such may still be assembled uniformly, as shown in Fig. 2. Another point of advantage lies in the ease of manipulation of the springs s on their block S, whereby absolute uniformity may be attained. Still another point is this that the block S may be detached from the flange a⁴ at any time and an instrument changed from one type of connection to another by simply changing the springs, or, on the other hand, the springs may be left in without disturbing the wire connections, and the mechanical parts of the hook may be taken out for repairs.

The making and breaking of contacts among the springs s is accomplished by having one spring longer than the others and by causing its insulated end s⁴ to lie in the slot h⁴, formed in a transverse projection on the hook extension h³. As the lever H goes up and down, therefore, the extension h³ is moved and shifts the contacts of the springs. Connection to the various springs is preferably made by soldering to tails formed on the sides thereof.

I am aware that many changes may be made in matters of detail without departing from the spirit of my invention; but all such changes, I wish it distinctly understood, are regarded as clearly within the scope and purview of my claims.

Having thus described my invention, what I claim, and desire to secure by Letters Patent, is—

1. In an electrical switch, the combination with a frame, an operating-lever pivoted thereon, a flange formed thereon, a metal block removably carried upon said flange, contact-springs removably mounted upon said block, whereby the block and springs

may be removed together or separately, and an operating connection between the lever and springs.

2. An electrical switch comprising a frame, 5 a pivot-post thereon, a lever mounted upon said pivot-post, an independent base carried by said frame above the pivot-post, a group of contact-springs secured together and mounted upon said base, an operating connection between the lever and the springs, and an operating-spring secured to the frame and extending around the lever to engage the same forward of the pivot-post.

3. An electrical switch comprising the following instrumentalities: a frame, a flange carried thereby, contact-springs carried by said flange, a pivot-post on the frame, an operating-lever having a notch in its under side and adapted to engage said pivot-post, an 20 extension on said lever adapted to form an operating connection with the contact-springs, means for limiting the movement of the lever, and a spring carried by said flange and extending into engagement with the 25 notch of the lever so as to normally hold the forward end thereof in raised position.

4. A telephone switch-hook for wall sets comprising a frame having a front plate at right angles to the body of the frame, contact- 30 springs mounted upon the frame, an operating-lever passing through an aperture in said front plate and pivoted on the side of the frame, with an operating connection for said contact-springs, means for normally holding 35 the lever in raised position, and an escutche-

on-plate for the front plate, all parts of the switch being of smaller dimensions laterally than said escutcheon.

5. In a telephone switch-hook, the combination of a frame having an apertured integral front plate, a switch-hook pivoted on the frame and projecting through the front plate, a flange on the frame, switch-springs removably secured to said flange, a notched rearward extension on said switch-hook adapted 45 to form an operating connection between the same and the springs, and an actuating-spring carried by said flange and engaging the switch-hook on its under side forward of its pivotal point so as to normally hold the 50 switch-hook in raised position.

6. In a telephone-switch, the combination with a frame having an apertured front plate, a pivot-post on said frame, a flange carried by said frame, contact-springs supported by 55 said flange, an operating-lever extending through the aperture in the front plate, lying between the springs and the frame in engagement with the pivot-post, and having an operating connection with the springs, together 60 with means carried by the flange for holding the forward end of said lever in raised position.

In testimony whereof I affix my signature in presence of two witnesses.

ERNEST W. BRACKETT.
